UNITED STATES PATENT OFFICE

FRANZ HIRSCHWALD, OF BERLIN, GERMANY

SLEEVE-LENGTH-ADJUSTING DEVICE

Application filed January 28, 1930, Serial No. 423,971, and in Germany August 29, 1929.

This invention relates to new and useful means for retaining a tuck made in a sleeve, more particularly a shirt sleeve for shortening the sleeve thereby withdrawing the wrists 5 bands from the wrists.

The object of this invention is to provide a device of the kind, hereinafter described which, in comparison with other devices of the kind, hitherto known, differs, first, in 10 that it can be made flat or slightly arched so that it will fit well against the arm and will not, in any way injure or rumple the material gripped or that lying adjacent thereto. A further important advance, in 15 comparison with the arrangements already known, consists in that the intensity of the clamping action is not dependent upon a spring. By this device the length of a sleeve can be expeditiously shortened and it can be 20 operated by one hand only so that its use is rendered simple, easy and convenient.

According to this invention, a ring, through which a tuck or pleated part of a sleeve is drawn, has hinged to it two hinged 25 members having clamping jaws facing each other, said clamping jaws being thus adapted to grip the bunched part of the sleeve between them and to hold it in this position when fastened by a suitable locking device.

A further object of this invention is to 30 make the ring elastic and to form it so that it has opposite to the bearing of the hinged oscillating members incurvations, in which the ends of these members are held in the 35 clamping position of the clamping jaws. Consequently the oscillating members have a smaller length than the diameter of the ring, on which these members are guided.

The ring with its incurvations serves there- 40 fore for drawing the pleated part through it, as a guiding member for the sliding ends of the oscillating members and as an elastic locking device for these members. Preferably the inward bent incurvations of the 45 ring are formed slantingly to each other so that a good clamping is also possible, if the pleated part is thicker than usual.

A constructional example of the tuck or 50 pleat holder is shown in the accompanying drawings in which:

Figure 1 is a front view of the device with the clamps in open position.

Figure 2 is a front view of the device with the clamps in half open position.

Figure 3 is a front view of the device with 55 the clamps in closed position.

Figure 4 is a side view of the device showing the bunched material drawn through the device.

The ring-shaped member 1 made of elastic material is provided with a bearing 2 for two oscillating members 7, hinged with one end 9 to this bearing 2. The oscillating members 7 are preferably covered with a rubber sheet or cover 3 and serve thus as clamping jaws. The other ends of the oscillating members 7 are formed with eyes 8, guided on the ring 1. The length of these hinged oscillating members 7 is somewhat smaller than the 60 diameter of the ring 1. Opposite to the bearing 2 for these members 7 the ring 1 has incurvations 4 being nearly so proportioned that the eyes 8 of the oscillating members 7 are placed in the clamping position in the 65 lowest point of these incurvations 4 without putting the ring 1 out of shape as shown in Figure 3. These inward bent incurvations 4 are so formed that the sides 5 of these incurvations extend slantingly to each other. The ring 1 may be provided with a projection 70 6 between the two incurvations 4, in order to give a good pressing point for the employment of this device.

The operation of this device will now be understood to be as follows. The device is 75 laid on the material to be bunched, as shown in Figure 1. After having drawn the tuck or pleated part of the sleeve through the ring 1 between the clamping jaws 3, the oscillating members 7 with the clamping jaws 3 are 80 pressed against each other, whereby the ring 1 is put out of its normal shape, that means, it will take a form according to Figure 2, which can be compared with an ellipse caused by the length of the oscillating members 7 85 being shorter than the diameter of the ring 1.

In the operative position, that is to say the 90 clamping position, the oscillating members 7 reach the incurvations 4, so that the ring 1 95 may spring back to its normal shape, thereby 100

forcing the eyes 8 with the clamping jaws 3 to take a position in the lowest point of the incurvations 4 by means of the slanting arrangement of the sides 5. In this position 5 the bunched material is well fastened. By pressing upon the projection 6 and the bearing 2 the eyes 8 of the clamping jaws 3 are released by the incurvations 4 of the ring and caused to move apart by means of the 10 bunched material thereby releasing the pleated part.

Further the parts of the device can be made of curved or other suitable formation to conform to the arm as shown in Figure 4, and 15 other modifications may be adapted which do not exceed the scope of the invention.

What I claim and desire to secure by Letters Patent of the United States is:—

1. A sleeve-length adjusting device comprising a ring of elastic material, clamp-supporting members hinged to the ring, a clamping-jaw on each hinged member, an eye on the free end of each hinged member, said eye being guided on the ring, each hinged 20 member having a smaller length than the diameter of the ring, and a locking device on the ring, opposite to the bearing for the hinged members and cooperating with said eyes for locking the hinged members in the 25 clamping position of the device.
2. A sleeve-length adjusting device comprising a ring of elastic material, clamp-supporting members hinged to the ring, a clamping-jaw on each hinged member, an eye on 30 the free end of each hinged member, said eye being guided on the ring, each hinged member having a smaller length than the diameter of the ring, and a locking device on the ring, comprising two incurvations with slanting 35 sides opposite to the bearing for the hinged members and cooperating with said eyes for catching said latter and locking the hinged members in the clamping position of the device.
- 40 3. A sleeve-length adjusting device comprising a ring of elastic material, clamp-supporting members hinged to the ring, a clamping-jaw on each hinged member, an eye on the free end of each hinged member, said eye 45 being guided on the ring, each hinged member having a smaller length than the diameter of the ring, a locking device on the ring, comprising two incurvations with slanting sides opposite to the bearing for the hinged 50 members and cooperating with said eyes for catching said latter and locking the hinged members in the clamping position of the device and a projection between the two incurvations projecting beyond the circumference of the ring.

DR. FRANZ HIRSCHWALD.
